UNITED STATES PATENT OFFICE

ARTHUR J. FREEMAN, OF ALAMEDA, CALIFORNIA

SHEET SEPARATOR AND CONVEYER

Application filed March 5, 1929. Serial No. 344,353.

My invention relates to a machine for automatically separating and conveying a single sheet of material from a magazine containing a plurality of such sheets to a printing position, holding it in contact with a printing plate for a predetermined period of time and then discharging it from the machine.

An object of my invention is to provide a device in which a pneumatic suction cup is mounted integral with a platen and will recess into the face of the platen and serve as a portion thereof during the time that the platen is holding a sheet in contact with a printing plate and a means for positioning the platen and cup, adjacent a stack of sheets, so that when suction is applied to the cup it will separate and remove a single sheet from the stack.

Another object of my invention is to provide a machine of the character described in which the sheets in the magazine are held in approximately a horizontal position while the printing plate is in a perpendicular or inclined position.

A further object of my invention is to provide a device which will separate and remove from a stack one sheet only at each operation.

A still further object of my invention is to provide a pneumatic suction cup which will flex the sheet to be separated and lift it so that the lift will begin at the outer edge and progress inwardly.

My invention possesses other objects and features of advantage, some of which, with the foregoing, will be set forth in the following description of the preferred form of my invention which is illustrated in the drawings accompanying and forming a part of the specification.

While my machine is perfectly adapted to the printing of photographs, it is to be understood that I do not limit myself to this one adaptation nor to the showing made by the said drawings and description, as I may adopt variations of the preferred form within the scope of my invention as set forth in the claims.

Referring to the said drawings:

Fig. 1 is a side view of my invention with some of the parts broken away to show parts

that would otherwise be hidden and shows the platen in normal position in full lines and in contact position in dotted lines. Fig. 2 is a side view, partly in section, of the pneumatic sheet separating device, showing in dotted lines the shape and position of the suction cup before the suction is applied and in full lines the shape and position of the cup and sheet after the suction is applied. Fig. 3 is a front elevation of the sheet magazine and suction cup, showing how the cup flexes and lifts the topmost sheet when the suction is applied. Fig. 4 is a sectional view on lines 2-2 of Fig. 5, showing the normal shape of the suction cup. Fig. 5 is a plan view of the suction cup. Fig. 6 is a plan view of the machine as shown in Fig. 1. Fig. 7 is a sectional view on lines 1-1 of Fig. 1. Fig. 8 is an enlarged view of cam 16 and co-operating parts.

In the drawings, A represents a frame in which the various parts of my invention are mounted, this frame being disposed in substantially a horizontal position with the exception of the member A' which extends upward at an angle slightly inclined from the perpendicular. The member A' is formed with a recess for holding a plate 1, which may be a photographic negative from which it is desired to make prints.

Extending across and between the sides of, and journaled in, the frame A is a rocker shaft 2, to which is rigidly attached a pair of arms 3. To and between the outer ends of these arms a platen 4 is pivotally mounted and adapted to have a rocking movement, about said pivot, controlled by a link 5, one end of which is pivoted to the platen and the other to the frame A. The platen is designed to also have a reciprocating movement to and between a stack of sheets 6, supported within the frame A, and the plate 1. This movement is produced by a grooved cam 7 which when rotated will deliver a rocking movement to the lever 8, fixed on the shaft 2, and carrying on its outer end a roller 9 adapted to fit the groove in the cam. The pivots 10 and 11 of link 5 are so located, relative to the arms 3 and the frame A, that the platen, when in a normal position as shown by solid

70

75

79

83

89

93

99

103

109

lines in Fig. 1, will be disposed over and at an acute angle with the stack of sheets 6, and when in a printing position, as shown by dotted lines in Fig. 1, will be swung parallel to the plate 1.

Slidably mounted in a suitable bearing, extending through the platen 4, is a tubular stem 12, designed to have reciprocating movement. On the inward end of this stem is mounted a flexible cup shaped member 13, composed of rubber or the like, and which for convenience will be termed a suction cup.

Extending laterally across and through suitable journals in the platen 4 is a rocker shaft 15, the ends of which are rigidly attached to the arms 3. Mounted on this shaft is a cam 16 adapted to be operated by the shaft and also to have a limited free movement about the shaft. This cam is so located on the shaft that its face will be directly beneath and bear against a lever 17, the inner end of which is pivoted to a block 18 fixed on the outer end of the stem 12. In the outer end of lever 17 is a slot 19 which fits a stationary pin 20. This slot allows the lever to have a reciprocating movement longitudinally and also a rocking movement about the pin.

When the platen 4 is swung upward to its printing position and is rocked on the shaft 15 by the link 5, the cam 16, after a time will be engaged by the drive pin 21 and will have an outward movement in relation to the platen and will lift the inner end of the lever 17 and move the stem 12 to its upward position, against the pressure of the leaf spring 22, which position is attained when the platen 4 arrives at a printing position, as is shown by dotted lines in Fig. 1. When the platen moves downward on its return to the normal position, the cam 16 will be free for a time to turn on the shaft 15 and due to the pressure exerted by the spring 22 and the friction between the cam and the lever 17, the cam will maintain the outward position, relative to the platen, until the platen has nearly reached its normal position, at which time the cam is engaged by the drive pin 21, and after being moved a few degrees, will get past center and the spring 22 will instantly move the stem 12 to its downward normal position.

The suction cup 13 is so mounted on the stem 12 that it will be normally disposed approximately parallel with the face of the platen 4 and at a distance therefrom, but, when the stem 12 is moved to its upward position, it will be drawn into the recess 23 provided therefor in the face of the platen. A perforation 24 in the suction cup communicates with the hole in the tubular stem 12, through which air may be withdrawn or discharged to alternately create or break a vacuum in the cup. This cup is designed to serve as a sheet separating means and also as a means for conveying sheets to, and in con-

junction with the platen 4, for holding them into contact with plate 1; this purpose is accomplished by temporarily altering the shape of the cup at predetermined times. The cup is formed with a sealing rim 25 and for the purpose of separating a sheet from the stack, is brought into contact with the sheet, held at an angle as is shown in Fig. 1. The shape of the cup, owing to its flexible nature, will be altered when brought against the sheet so that the sealing rim will, at all points, come into contact with the sheet and form a seal enabling the air to be withdrawn from between the cup and the sheet, thereby affixing the sheet to the cup. An air pump 26 is provided for this purpose. The body 27 of the cup, being of heavier material, will maintain its shape and the lower side thereof will be held firmly against the sheets. As the air is withdrawn from the cup the atmospheric pressure will cause the cup to flatten and the free section of the rim will lift and the sheet affixed thereto will be flexed and lifted, the lift beginning at the outer edge and progressing inwardly, as is shown in Figs. 2 and 3. The inherent resistance of the sheets to flexure produces a downward pressure, at the edge, on all of the underlying sheets when the attempt is made to flex them, which results in an action that, due to the lift beginning at the edge, allows air to enter between the outermost sheet and the one immediately beneath it, thus effecting a separation of the sheets and preventing more than one being carried away at a time.

Extending inwardly for a distance from the frame brackets 28, and above the outermost sheet in the stack 6, are the projections 29. Extending inwardly for a distance, and over, and at a distance above, and situated near the inward end of the stack 6, are the members 30, and these, together with the projecting members 29, serve to hold the edges of the sheets down, and when a sheet is being lifted produce a slight relative action between the sheets, which action, assists in their separation and enables the sheets to be separated at a high rate of speed.

When the suction cup with a sheet affixed thereto is carried by the platen to a printing position, it is withdrawn into the recess 23, and as the sheet is placed into contact with the plate 1, the cup will be further flattened, and due to the recess into which the cup fits, will, with the platen, present a continuous flat surface which will hold the sheet into contact with the plate at all points.

Extending across and through suitable journals in the frame A is the drive shaft 31, adapted to be continuously rotated by a pulley 32, fixed to the outer end thereof, from any suitable source of power. This shaft also carries the cam 7, and the pump cam 33 which delivers the outward stroke to the piston of the double acting air pump 26 through a lever

34. This lever has one end attached to the piston of the pump and the other end pivoted to the frame A and has mounted, near its longitudinal center, a roller 35 to engage the face of the cam 33. The inward stroke is delivered to the piston by the spring 36. The air intake and outlet of the pump is connected with the suction cup 13 through the hollow stem 12 and the flexible tubing 37, a portion 10 of which has been cut away in the drawings. The operation of the pump is synchronous with that of the platen 4 and is so timed as to create a suction in the cup when the platen is in one position and to discharge air through 15 the cup when the platen is in another position, the object of which will be presently described.

The stack of sheets 6 are held in a proper position within the frame A by the brackets 20 28-38-39-40 and the spring members 41 which bear inwardly against the edges of the sheets, and in the event that any of the sheets are moved from their true position by the separating and conveying action, these springs 25 will again position them against the brackets 39.

Supporting the sheets in the stack is a plate 42, from which depends a rod 43 slidably fitted in a bearing 44. This rod is urged upward by means of a spirally wound spring 45 which has its outer end fixed to the shaft 43 and its inner end attached to the frame A. Upward movement of the stack as a whole is limited by a lever 46 slidably mounted in a 30 slotted bearing, on and, parallel to the frame A, its upper right angle end extending inward for a distance over and above the stack of sheets. This lever is designed to have reciprocal movement, and at predetermined times, will lift to allow the topmost sheet of the stack to be removed. The upward movement of the whole stack is prevented at this time by the adjustably mounted tapered wedge 47, held and operating in a tapered longitudinal channel formed in the bearing 44 of shaft 43. The wedge is adapted to have one of its sides bear against the shaft while the opposite side bears against the bottom of the channel, and may be moved upwardly or 45 downwardly so as to wedge between the surfaces or lie loosely therebetween, thereby respectively locking the shaft against movement or allowing it to move in the direction of urge of the spring 45, and when moved upwardly toward the shallow end of the channel will wedge between the shaft and the bottom of the channel and prevent any upward movement of the shaft. The wedge is normally held in this wedged position by a leaf spring 48, one end of which is attached to the frame A and the free end bearing against the outer end of the wedge.

After a sheet has been removed from the stack and has been carried to a printing position with the platen 4, the movement of the

link 5, operating through the link 49 and the bell crank 50, will cause the lever 46 to move to its lower position, which position determines the location for the topmost sheet in the stack 6. At the same time the cam 51, 70 attached to the bell crank 50, bears downward on the upper end of the wedge 47 moving it downward and freeing the shaft 43, which, by virtue of the urge of spring 45, moves the stack of sheets upward a distance 75 equal to the thickness of the sheet just removed and against the right angle end of lever 46.

In operation, the shaft 31 is constantly rotated through the pulley 32, from any suitable source of power. Assume the parts to be in the position shown in Fig. 1 in which the suction cup 13 is in position to separate the topmost sheet in the stack; as the shaft 31 is rotated in the direction shown by the arrow 80 on cam 7, the roller 9 travels on the concentric section 52 of the cam 7, and the platen 4 is without movement; but during this period, the pump cam 33 is moving the piston of pump 26 downward and exhausting the air 85 from the suction cup, causing it to grip the topmost sheet and separate it, as previously explained, from the remainder of the stack. As the roller 9 passes to the eccentric portion 53 of the cam 7, the lever 8 is forced downward and the arms 3 carry the platen, and the sheet affixed to the cup 13, upward and against the plate 1. During this upward movement of the platen 4 the link 5 has caused it to change its position, relative 90 to the arms 3, by rocking it on the shaft 15; and the cam 16 has, through the lever 17, drawn the suction cup back into a recess 23 formed in the platen 4. The link 5 in its upward movement has, through the connecting link 49 and bell crank 50, moved the lever 46 to its downwardmost position and the cam 51 has moved the wedge 47 outward, thereby releasing the shaft 43 and allowing the stack of sheets 6 to be moved, by the urge of spring 45, upward and against the angular end of the lever 46. The roller 9 having now reached the concentric portion 54 of the cam 7, the platen 4 is held against the plate 1 during the period required for the roller to pass over 100 this section of the cam; during this period the sheet, held by the suction cup, is pressed, by the platen and cup, into close contact with the plate 1 and may be submitted to the action of a light 55. When the roller 9 reaches the eccentric section 56 of the cam 7 it moves upward and the platen 4 is drawn away from the plate 1 carrying the printed sheet away with it a short distance; at this point the cam 33 allows the spring 36 to move the piston in the pump 26 to the upper end of the cylinder, 105 exhausting air through the cup 13 and releasing the sheet held thereby which is then carried away by gravity into the guide chute 110 57 through which it is discharged from the ma-

chine. After traveling over section 56 of cam 7 the roller 9 reaches the starting point and the cup 13 is again in position to grasp and separate another sheet.

5. From the foregoing it will be seen that I have provided a sheet separator and conveyer which may be operated continuously and which will separate a single sheet from a stack, convey it to a printing position, place 10 it into contact with a plate for a predetermined period of time and then discharge it from the machine. I have provided a positioning of the sheet magazine and the printing plate so that the sheets may lie in a horizontal position in the magazine but will be 15 in an inclined or perpendicular position at the plate so that, after being released, they will be carried from the printing position by gravity, this positioning also provides a 20 short conveyage distance from the magazine to the printing plate so that only a minimum amount of time will be spent on the trip between the magazine and the plate. I have provided a means for elevating the sheets in 25 the magazine which will maintain the top-most sheet in the stack at the proper level regardless of the number or the varying thicknesses of the sheets. I have also provided means whereby a flexible suction cup will effectively 30 separate a single sheet from a stack and also serve as a sheet holding means while the sheet is being conveyed to and against a plate, and, during the treatment of said sheet, will serve as a part of the platen for holding 35 the said sheet into contact with the plate, and after treatment will remove the sheet from the plate.

I claim:

1. In a sheet separator and conveyer a 40 magazine for holding a stack of sheets, means for holding a printing plate in an inclined or perpendicular position relative to the face of the sheets, a platen adapted to travel to and between the stack and the plate, a sheet 45 holder mounted on said platen, means for swinging the platen so that its face will be inclined relative to the face of the sheets when in one position and when in another position will be parallel to the said plate and means 50 for operating the platen and sheet holding means to convey sheets from the magazine to the plate.

2. In a sheet separator and conveyer a 55 magazine for holding a plurality of sheets, means for positioning the outwardmost sheet at a definite outward position in the magazine, a flexible suction cup, means for bringing said cup into contact with the outwardmost sheet in the magazine, means for affixing the sheet to the cup, means for altering 60 the shape of the cup to flex and separate the affixed sheet from the other sheets in the magazine, means for removing the separated 65 sheet from the magazine and means for mov-

ing the succeeding sheet into the said outward position.

3. In a machine of the character described a magazine for holding a stack of sheets to be printed, means for holding a printing plate, means for holding the outwardmost sheet in the stack at a definite outward position in the magazine, a sheet carrier adapted to be projected into the magazine to grasp and separate a single sheet from the stack 75 then carry it from the magazine to and against the plate then hold it into contact with the plate for a predetermined period of time then remove it from the plate and means for moving the succeeding sheet of the stack 80 into said outward position in the magazine.

4. In a sheet separator and conveyer a flexible pneumatic sheet gripping member, an oblique position for said member relative to and against the outwardmost sheet in a 85 stack, means for affixing the sheet to the member while in said oblique position, means for temporarily altering the shape of the member, and means employing the member and the oblique position together with the temporary change in shape to separate the affixed sheet from the stack.

5. In a sheet separator and conveyer a flexible pneumatic sheet gripping member, means for bringing said member into engaging 95 position with the outwardmost sheet of a stack while in an oblique position relative thereto, means for producing suction between the member and the sheet to first affix the sheet to the member then temporarily change the shape of the member to flex and cause a separation of the affixed sheet from the stack.

6. In a sheet separator and conveyer a flexible pneumatic sheet gripping member having a sealing rim, an oblique engaging position for said member relative to and against the outwardmost sheet of a stack, means for altering the shape of the member to bring all points on the sealing rim into contact with the said sheet, means for producing suction between the member and the sheet to first affix the sheet to the member and then temporarily change the shape of the member to flex and cause a separation of the affixed sheet from the stack.

7. In a machine of the character described a means for holding a printing plate, a magazine for holding a stack of sheets to be printed, a platen adapted to travel from the magazine to the plate, means for rocking the platen to change its angular position relative to the plate when at the magazine, a sheet gripper, means for projecting said gripper into the magazine to engage a sheet then separate it from the underlying sheet then withdraw it from the magazine, means for conveying the sheet to the plate for treatment, means for discharging the printed sheet and means for holding the outwardmost sheet in the 100 105 110 115 120 125 130

stack at a definite outward position in the magazine.

8. In a sheet separator and conveyer a means for holding a printing plate, a magazine for holding a stack of sheets to be printed, a platen adapted to travel and carry sheet material from the magazine to the plate, a pneumatic sheet gripper on said platen, an oblique sheet engaging position for said gripper relative to and against the outwardmost sheet in the magazine, means for affixing a sheet to the gripper, means for releasing the sheet after treatment at the plate and means employing said oblique position to facilitate sheet separation.

9. In a sheet separator and conveyer a means for holding a printing plate, a magazine for holding a stack of sheets, a sheet carrier adapted to travel from the magazine to the plate, a pneumatic sheet gripper on said carrier, means for rocking said gripper so that when at the plate it will be parallel therewith and when at the magazine it will be inclined relative to the sheets in the stack.

25 10. In a sheet separator and conveyer means for holding a printing plate, a magazine for holding a stack of sheets, means for positioning the outwardmost sheet in the stack at a definite outward position in the magazine, a sheet gripper, means for affixing a sheet to the gripper and for warping the gripper to flex and raise the sheet edge, means for withdrawing the raised sheet from the magazine and for conveying it to a printing position on the plate, means for flexing the sheet edge while it is being withdrawn to facilitate sheet separation, means for removing the sheet from the plate after treatment and means for discharging it from the machine.

40 11. In a sheet separator and conveyer a flexible pneumatic member adapted to grasp, separate and lift a single sheet from a stack, means for producing suction between the member and the outwardmost sheet in the stack to first affix the sheet to the member then warp the member to flex and lift a portion of the affixed sheet and a second means for flexing the sheet while it is being lifted from the stack to facilitate sheet separation.

45 12. In a sheet separator and conveyer a magazine for holding a stack of sheets to be printed, means for maintaining the outwardmost sheet of the stack at a definite outward position in the magazine, means for holding a printing plate in a position parallel or inclined relative to the perpendicular face of the stack, a sheet carrier adapted to travel from the magazine to the plate, a sheet gripper on said carrier, means for separating a single sheet from the stack, means for operating the sheet gripper and carrier to convey the separated sheet to the plate for treatment, means for removing the sheet from the plate

after treatment and for discharging it from the machine.

13. In a sheet separator and conveyer a printing plate, a magazine for holding a stack of sheets to be printed, a platen adapted to have reciprocating movement to and between the magazine and the plate, means for rocking the platen to change its angular position relative to the plate when at the magazine, a sheet gripper on the platen, means for projecting said gripper into the magazine to grasp a sheet when the platen is at the magazine and means for withdrawing it into the platen when the platen is at the plate.

70 14. In a sheet separator and conveyer a magazine for holding a stack of sheets to be printed, means for holding a printing plate in a position parallel or inclined relative to the perpendicular face of the stack, a platen and sheet gripper adapted to travel from the magazine to the plate, means for projecting said gripper into the magazine to grasp and withdraw a single sheet, means for flexing the sheet at its edge while being withdrawn to facilitate sheet separation and means for operating the platen and sheet gripper to convey sheets from the magazine to the plate.

75 15. In a machine of the character described a magazine for holding a stack of sheets to be printed, means for holding a printing plate in a position either parallel or inclined relative to the perpendicular face of the stack, means for positioning the outwardmost sheet in the stack at a definite outward position in the magazine, automatic means for separating a single sheet from the stack carrying it to and holding it into contact with the plate for a predetermined period of time then removing it from the plate then discharging it from the machine and mechanism for effecting the several operations successively and continuously.

80 16. In a sheet separator and conveyer a magazine for holding a stack of sheets, means for holding a printing plate in a position either parallel or inclined relative to the perpendicular face of the stack, a platen and sheet gripping means adapted to travel from the magazine to the plate, means for gripping and separating a single sheet from the stack, means for operating the platen and sheet gripper to convey sheets from the magazine to the plate and means for rocking the platen to change its angular position relative to the plate when at the magazine.

85 17. In a sheet separator and conveyer a magazine for holding a stack of sheets to be printed, means for holding a printing plate in a position parallel or inclined relative to the perpendicular face of the stack, a platen and sheet gripper adapted to travel from the magazine to the plate, means for projecting said gripper into the magazine to grasp a sheet then separate it from the underlying sheet then withdraw it from the maga-

zine and means for flexing the sheet while being withdrawn to facilitate sheet separation.

18. In a sheet separator and conveyer means for holding a printing plate, a magazine for holding a stack of sheets, a sheet carrier adapted to convey sheets from the magazine to the plate, a flexible pneumatic sheet gripping member, an oblique sheet engaging position for said member relative to and against the outwardmost sheet in the stack, means for affixing the sheet to the member, means for temporarily changing the shape of the member and means employing the member and the oblique position together with a temporary change in the shape of the member to separate the affixed sheet from the stack.
